UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,142,478.

Specification of Letters Patent.

Patented June 8, 1915.

Application filed February 3, 1912. Serial No. 675,290.

To all whom it may concern:

Be it known that I, LEWIS C. BAYLES, a citizen of the United States, and resident of Easton, in the county of Northampton and State of Pennsylvania, have invented a new and useful Improvement in Percussive Tools, of which the following is a specification.

The object of this invention is to provide 10 a novel rotation device by means of which the drill steel may be rotated by both movements of the work piston, thereby securing a substantially continuous rotary movement of the steel during the operation of the tool.

15 The object of this invention is furthermore to provide certain novel features of construction which will bring the parts into very compact and convenient arrangement and in which the parts may be readily assembled and disassembled.

In the accompanying drawings, Figure 1 represents in longitudinal central section, a percussive tool of the piston hammer type with my improved rotation device applied thereto. Fig. 2 is a longitudinal central section through the tool, taken in the plane of the line A—A of Fig. 1, Fig. 3 is a transverse section taken in the plane of the line B—B of Fig. 1, and Fig. 4 is a diagrammatic view showing more clearly the construction of the controlling valve and the location of the passages controlled thereby.

The work piston is denoted by 1 and the chamber within which it reciprocates, by 2. 35 The cylinder in which the work piston 1 is located, is denoted by 3, its front head by 4, its front head washer by 5, its back head by 6, its valve chest by 7, its rotation controlling piston chest by 8, and its handle by 40 9.

The oscillating rotation controlling piston is denoted by 10 and its chamber by 11. The controlling valve 12 in the valve chest 7, may be of any well known or approved form and is arranged to control the reciprocations of the work piston 1 and the rotation controlling piston 10. It is herein shown as of the well known double winged type in which one wing controls the admission of motive fluid from the inlet 33 to the 50 opposite ends of the work piston chamber 2 and rotation controlling piston chamber 11 through the passages 34, 35, and 36, 37, and the other wing controls the exhaust from the work piston chamber 2 to the outlet 38, 55 through the passages 39, 40. This rotation

controlling piston 10 oscillates in a right line across the tool at right angles to the movement of the work piston 1.

The shank of the drill steel 13 is fitted to the bore of the chuck 14, which chuck is rotatably mounted in the front head 4. This drill steel 13 is arranged in position to have its rear end struck by the extension 15 of the piston 1, which extension slides through the front head washer 5 into the enlarged bore 16 of the chuck 14. This chuck is provided with a spur gear 17 which meshes with pinions 18, 19, carried by the front ends of rotary shafts 20, 21, which extend longitudinally from front to rear of the tool through the cylinder 3, washer 5 and valve chest 7, into the front head 4 and rotation controlling piston chest 8.

Ratchet levers 22, 23, are loosely mounted to rock on the rear ends of the rotary shafts 20, 21, the free ends of which levers are extended into a slot 24 in the oscillating rotation piston 10. These levers 22, 23, are provided with ratchet teeth 25, 26, on their back ends which are arranged to be engaged by spring-pressed ratchets 27, 28, having a sliding interlocked connection with the shafts 20, 21. The springs 29, 30 for holding these ratchets 27, 28, in engagement with the ratchet levers 22, 23, are interposed between the ratchets 27, 28, and washers 31, 32, interlocked with the shafts 20, 21. The interlocking engagement with the rear ends of these shafts 21 with the ratchets 27, 28, and washers 31, 32, is provided for, in the present instance, by forming the rear ends of these shafts angular in cross section and the bores of said ratchets and washers of a similar shape in cross section.

The direction of the engaging teeth on the ratchets 27, 28, and the levers 22, 23, is such that as the rotation controlling piston 10 moves in one direction, one shaft 20 will be rotated and when it is moved in the other direction, the other shaft will be rotated. This will impart an almost continuous rotary movement through the pinions 18, 19, to the chuck 14, and thereby to the drill steel 13.

It will be seen that the construction herein shown and described is very simple and compact and may be readily assembled and disassembled.

While I have shown this invention in connection with a percussive tool of the piston

hammer type, I do not wish to limit myself to such a tool, but contemplate the use of the invention in connection with percussive tools of any type.

What I claim is:

1. In a percussive tool, a chuck and means for rotating it comprising two shafts connected to the chuck and a piston arranged to be alternately clutched to and released 10 from the shafts.
2. In a percussive tool, a chuck and means for rotating it comprising two shafts connected to the chuck and a fluid pressure operated piston arranged to be alternately 15 clutched to and released from the shafts.
3. In a percussive tool, a chuck and means for rotating it comprising two shafts, gears connecting the shafts and chuck, a piston and clutch connections between the piston 20 and shafts arranged to be alternately operated.
4. In a percussive tool, a chuck and means for rotating it comprising two shafts, gears connecting the shafts and chuck, a fluid 25 pressure operated piston and clutch connections between the piston and shafts arranged to be alternately operated.
5. In a percussive tool, a chuck and means for rotating it comprising two shafts extending longitudinally from front to rear of 30 the tool, driving connections between the chuck and the front ends of the shafts, a piston and driving connections between the piston and the rear ends of the shafts arranged 35 to be alternately operated.
6. In a percussive tool, a chuck and means for rotating it comprising two shafts extending longitudinally from front to rear of the tool, driving connections between the 40 chuck and the front ends of the shafts, a fluid pressure operated piston and driving connections between the piston and the rear ends of the shafts arranged to be alternately operated.
7. In a percussive tool, a chuck and means for rotating it comprising two rotary shafts extending longitudinally from front to rear of the tool, gears connecting the chuck with the front ends of the shafts, a piston and 50 clutch connections between the piston and the rear ends of the shafts arranged to be alternately operated.
8. In a percussive tool, a chuck and means for rotating it comprising two rotary shafts extending longitudinally from front to rear of the tool, gears connecting the chuck with the front ends of the shafts, a fluid pressure 55 operated piston and clutch connections between the piston and the rear ends of the shafts arranged to be alternately operated.
9. In a percussive tool, a chuck and means for automatically rotating it comprising a shaft, a driving connection between the shaft

and the chuck, a rotation controlling piston, a rock lever engaged by the piston and a driving connection between lever and shaft.

10. In a percussive tool, a chuck and means for automatically rotating it comprising a shaft, a driving connection between the shaft and the chuck, a fluid pressure operated piston, a rock lever engaged by the piston and a driving connection between said lever and shaft.

11. In a percussive tool, a chuck and means for rotating it comprising two shafts, driving connections between the shafts and chuck, a piston, rock levers engaged by said piston and driving connections between said levers and their respective shafts arranged 80 to be alternately operated.

12. In a percussive tool, a chuck and means for rotating it comprising two shafts, driving connections between the shafts and chuck, a fluid pressure operated piston, rock 85 levers engaged by said piston and driving connections between said levers and their respective shafts arranged to be alternately operated.

13. In a percussive tool, a chuck and means for automatically rotating it comprising a shaft, gears connecting the shaft with the chuck, a rotation controlling piston, a rock lever engaged by said piston and a clutch connection between the rock lever 95 and shaft.

14. In a percussive tool, a chuck and means for automatically rotating it comprising a shaft, gears connecting the shaft with the chuck, a fluid pressure operated rotation controlling piston, a rock lever engaged by said piston and a clutch connection between the rock lever and shaft.

15. In a percussive tool, a chuck and means for rotating it comprising two shafts, 105 gears connecting the shafts with the chuck, a piston, two rock levers engaged by said piston and clutch connections between the rock levers and their respective shafts arranged to be alternately operated.

16. In a percussive tool, a chuck and means for rotating it comprising two shafts, gears connecting the shafts with the chuck, a fluid pressure operated piston, two rock 115 levers engaged by said piston and clutch connections between the rock levers and their respective shafts arranged to be alternately operated.

In testimony, that I claim the foregoing as my invention, I have signed my name in 120 presence of two witnesses, this first day of February 1912.

LEWIS C. BAYLES.
